AUTOMATIC GUIDE FOR WEBS

William Thomas Armstrong, Gravesend, England

Application July 22, 1930. Serial No. 469,779, and
in Great Britain July 26, 1929

3 Claims. (Cl. 74—51)

The present invention relates to automatic guides for travelling sheets.

The object of the invention is to provide an automatic device for maintaining in a desired course, wires, felts or similar endless travelling bands, hereinafter referred to as the wire, on a paper making machine, cloth drying machine or any machine in which a web of paper, cloth, rubber or similar material travels over rollers.

10 In the usual form of device, commonly termed an automatic guide, a revolving roller is placed across the width of the wire, the roller being caused to revolve by contact with the "wire".

15 The bearings of the roller are so arranged that the bearing at one end of the roller may slide, whilst the bearing at the other end of the roller is pivoted, so that if the "wire" deviates from the desired course, the sliding bearing of the roller is moved either with or against the direction of the travelling "wire", and the "wire" is caused to resume the desired course.

20 The movement of the sliding bearing is usually obtained by the arrangement of a spade or feeler, or in some instances by two spades, maintained in contact with one or both edges of the "wire", the spade or spades being free to move any transverse movement of the "wire".

25 According to the invention a motor, automatically controlled by a feeler or feelers, is provided for causing displacement of said guide roller.

30 Preferably electrical contacts are arranged to operate either directly or indirectly by the movement of a spade or spades, and according to the direction of movement of the spades the circuit of an electric motor is thus completed for forward or reverse direction.

35 In the case of a paper making machine the guide may be operated by the "wire" itself making contact with metal spades or rollers arranged at each side of the machine. When the "wire" is running central no contact is made with either spade or roller but when the "wire" runs to one side contact is made and the guide motor is operated. When the "wire" moves to the opposite side contact is made with the other spade or roller and the guide motor moves in the opposite direction.

40 The electric motor may work on either an alternating current or a direct current supply, and through suitable gearing may give a sliding motion to one of the bearings of the guide roller, thus providing the means of correction of any transverse movement of the "wire" as above described.

45 Suitable electric limit switches may be pro-

vided to break the electrical circuit of the motor should the sliding bearing of the guide roller reach the predetermined limit of its travel in either direction.

50 The device may also be arranged for hand operation in the event of the failure of the electrical supply, and the motor and gearing may be provided with means of rapid disconnection for hand operation.

55 In the case of the "wire" being driven electrically the supply of the electric current for the motor driving the automatic guide could conveniently be arranged from the circuit of the electric motor driving the "wire".

60 The object of this invention is to render unnecessary the series of levers, links and bearings between the spade and the guide roller bearing as arranged on mechanical guides and to provide a connection between the spade and the guide 65 roller bearing which will eliminate the failures, frequent on mechanical guides, due to dirt, fibre, water and other foreign matter.

65 In addition, the object of this invention is to obviate the necessity for the continual movement 70 of wearing parts and to provide a means of acceleration of the rate of movement of the guide roller bearing, thereby accelerating the rate of correction of any transverse movement of the "wire".

75 If the transverse movement of the "wire" is slight, the rate of correction may be comparatively slow, owing to the guide motor not reaching its full speed before the correction has been effected, but if the transverse movement of the "wire" is 80 considerable, the motor may accelerate up to its maximum speed, thus providing the means of acceleration of the rate of movement of the guide roller bearing above mentioned.

85 Referring to the accompanying sheets of explanatory drawings:—

Figure 1 is a plan showing in solid lines the guide roll in its central position, and in dotted lines the guide roll moved against the direction of the travelling "wire". A portion of the "wire" 90 is also indicated.

Figure 2 is a similar plan, but showing in dotted lines the guide roller moved in the direction of the travelling "wire".

95 Figure 3 is an end elevation of the guide roller 105 shown in solid lines, in its central position, and in dotted lines moved against the direction of the travelling "wire". The sliding bearing with operating gear is also indicated in solid lines.

100 Figure 4 is a similar end elevation but shows in 110

dotted lines the guide roller moved in the direction of the travelling "wire".

Figure 5 is a side elevation of the sliding bearing of the guide roller showing suitable operating gear.

Figure 6 is an end elevation of the guide roller showing the spade in contact with the edge of the "wire", the spade being carried on a rod pivoted at a point below the spade.

10 Figure 7 is a similar end elevation showing the spade carried on a rod but pivoted at a point above the spade.

15 Figures 8, 9 and 10 show single mercury switches of the two-way type operated by the spade, in different positions of the spade.

19 Figures 11, 12 and 13 show double mercury switches of the one-way type operated by the spade, in different positions of the spade.

20 Figure 14 is a diagrammatical cross section through the "wire" showing metal spades arranged at both sides of the "wire".

25 Figure 15 is a similar diagrammatical cross section through the "wire" but showing metal rollers arranged at both sides of the "wire".

29 The same reference letters in the above figures indicate the same or similar parts.

In Fig. 1 the guide roller *a* is indicated in solid lines in its central position, the "wire" edges being indicated by the letters *bb*, the direction of the travelling "wire" by the arrow *c* and the direction of rotation of the guide roller by the arrow *d*. The guide roller is also shown in dotted lines in a position *a*¹ moved against the direction of the travelling "wire", the edges of the "wire" also in dotted lines, being indicated by the letters *b*¹*b*¹. The guide roller *a* is pivoted in a swivel bearing at point *e*, a sliding bearing being arranged at the other end of the roller. If the "wire" tends to move into the position *b*¹*b*¹, the guide roller will be moved into the position *a*¹ which will cause the "wire" to regain its central position *bb*. If the "wire" tends to move into the position *b*²*b*², indicated in Fig. 2, the guide roller will be moved into position *a*², also indicated on Fig. 2, which will similarly cause the "wire" to regain its central position *bb*. Fig. 3 shows an end elevation of the guide roller *a*, carried on a sliding bearing *f* having a projection *g* which is threaded to receive the screw spindle *h*. The sliding bearing is carried on a fixed bracket *f*¹. At the end of the spindle *h* is attached a worm wheel *i*, which meshes with the worm *j*, which in turn is driven, either directly or through suitable gears by an electric motor *k*. Alternatively the bearing *f* may be moved through any other suitable gearing by the motor *k*. A handle or handwheel *l* is connected to the spindle *h*, arrangement being made for disconnections by means of a clutch cast with the boss of the handwheel, or by any other suitable means. The guide roller is also indicated in dotted lines, in the position *a*¹, to which position it has been moved by the rotation of the screwed spindle to correct the tendency of the "wire" to move into the position *b*¹*b*¹ indicated in Fig. 1.

70 In Fig. 4, which is a similar end elevation, the guide roller is shown in dotted lines, in a position *a*², to which position it has been moved to correct the tendency of the "wire" to move into the position *b*²*b*² indicated in Fig. 2. It will be noted in Fig. 3 that in order to move the guide roller from the position *a* to the position *a*¹, the motor *k* will run in a certain direction, whereas in Fig. 4 to move the guide roller from the position *a* to the position *a*² the motor *k* will run in an opposite

direction to that in Fig. 3, in each case the movement having been effected through the medium of the spade and contacts.

Typical directions of rotation of the screw spindle *h* and of the motor *k* are indicated in Figs. 3 and 4, and it will be noted that the directions of rotation in Fig. 4 are opposite to those in Fig. 3, the actual directions of rotation, however, varying with the means of gearing employed.

80 The elevations on Figs. 6 and 7 show the guide roller *a* and the spade *n* in contact with the "wire" *o*, the spade being carried by a rod which may be pivoted either at a point *p* below the spade, as indicated in Fig. 6, or at a point *p*¹ above the spade as indicated in Fig. 7. The spade or spades may be arranged, supported in either of the two methods above, on either one or both sides of the "wire", and in a position either in close proximity to the guide roll as shown in Figs. 6 and 7, or at any other point of the "wire". The pivots *p* and *p*¹ may be arranged in such a position that one spade is maintained in contact with the "wire", or with a spade arranged on both sides of the "wire", the "wire" may not touch the spade when running between certain predetermined limits.

90 Figs. 8, 9 and 10 show the spade *n* fitted with a mercury switch *q* with electrical connections *r*, *s* and *t*. Fig. 7 indicates the spade *n* against the "wire" edge in its central position *b*, also indicated in Figs. 1 and 2, and it will be noted that the mercury *m* in this position of the switch *q* is making contact with the electrical connection *s* only, with the result that the motor *k* does not operate. 105 In Fig. 8 the spade *n* is against the "wire" edge in the position *b*², also indicated in Fig. 2. The mercury *m* in this position of the switch *q* is making contact with the electrical connections *s* and *t*, causing the motor *k*, indicated in Fig. 4, 110 to rotate in a direction suitable to bring the guide roller from its central position *a* to the dotted position *a*², also shown in Figs. 2 and 4. The guide roller in this position *a*² will then cause the "wire" to regain its central position *bb*. Fig. 9 115 indicates the spade *n* against the "wire" edge in the position *b*¹, also indicated on Fig. 1. The mercury *m* in this position of the switch *q* is making contact with the electrical connections *r* and *s*, causing the motor *k*, shown in Fig. 3, to 120 rotate in a direction suitable to bring the guide roller from its central position *a* to the dotted position *a*¹, also shown in Figs. 1 and 3. The guide roller in this position *a*¹ will then cause the "wire" to regain its central position *bb*. 125

Figs. 11, 12, and 13 show the spade *n* fitted with double mercury switches *q*¹ and *q*² with electrical connections *u*, *v*, *w* and *x*. It will be noted that the connections *u* and *v* are arranged nearer the "wire" edge than connections *w* and *x*. Fig. 11 130 indicates the spades *n* against the "wire" edge in its central position *b* also indicated in Figs. 1 and 2, and the mercury *m* in this position of the switches is not making contact with any of the electrical connections with the result that the motor *k* does not operate. In Fig. 12 the spade *n* is shown against the "wire" edge in the position *b*², also indicated in Fig. 2. The mercury *m* in this position of the switches *q*¹ and *q*² makes contact with the electrical connections *w* and *x*, 135 causing the motor *k*, shown in Fig. 4, to rotate in a direction suitable to bring the guide roller from its central position *a* to the dotted position *a*², also shown in Figs. 2 and 4. The guide roller in this position *a*² will then cause the "wire" to regain 140

85

90

95

130

135

145

150

its central position bb . Fig. 13 indicates the spade n against the "wire" edge in the position b^1 , also indicated on Fig. 1. The mercury m in this position of the switches q^1 and q^2 makes contact with the electrical connections u and v causing the motor k , shown in Fig. 3, to rotate in a direction suitable to bring the guide roller from its position a to the dotted position a^1 , also shown on Figs. 1 and 3. The guide roller in this position a will then cause the "wire" to regain its central position bb .

Fig. 14 is a diagrammatical cross section of the "wire", shown in solid lines in its central position bb in close proximity to metal spades y and y^1 arranged at both sides of the "wire". Electrical connections are arranged from these spades so that when the "wire" moves into the position indicated by chain dotted lines b^2b^2 , contact is made with the spade y and the motor k will rotate in a certain direction. When the "wire" moves into the position indicated by the dotted lines b^1b^1 , contact is made with the spade y^1 and the motor k will rotate in the opposite direction, causing the correction of the "wire" as previously described.

Fig. 15 is a similar diagrammatical cross section in which rollers z and z^1 take the place of the spades y and y^1 so that less frictional areas may exist.

30 I declare that what I claim is:—

1. An automatic guide arrangement for webs comprising a guide roller, bearings for said guide roller, an electric motor, gearing between the shaft of said motor and one of said bearings, whereby said guide roller can be displaced to one side or the other to maintain the web in a predetermined path, pivoted fingers adapted to contact with the edges of said web when the web is displaced from the predetermined path and having an unlimited and unobstructed travel, a switch case mounted on each of said pivoted fingers, electric contacts in the circuit of said

motor in said switch case and a freely displaceable element moving in said switch case under the action of gravity to bridge said contacts.

2. An automatic guide arrangement for webs comprising a guide roller, bearings for said guide roller, an electric motor, gearing between the shaft of said motor and one of said bearings, whereby said guide roller can be displaced to one side or the other to maintain the web in a predetermined path, fingers adapted to contact with said web when the web is displaced from the predetermined path and having an unlimited and unobstructed travel, a switch case mounted on each finger, electric contacts in said switch case in the circuit of said motor, freely displaceable elements moving in said switch case under the action of gravity to bridge said contacts and pivots supporting said fingers above their point of contact with the web, so that they are displaced against gravity by the edges of the web when the latter leaves the predetermined path.

3. An automatic guide arrangement for webs comprising a guide roller, bearings for said guide roller, an electric motor, gearing between the shaft of said motor and one of said bearings whereby said guide roller can be displaced to one side or the other to maintain the web in a predetermined path, switch contacts for controlling the energization and direction of movement of said electric motor, and means operated by the web when the web is displaced from the predetermined path for closing said switch contacts selectively, said closing means having an unlimited and unrestricted travel when operated by the web and operating during such displacement of the web to maintain the selected switch contacts closed until the web returns to its predetermined path without additional load on the web irrespective of the extent of its deviation from the predetermined path.
